UNITED STATES PATENT OFFICE.

GUSTAVE M. NELL, OF DENVER, COLORADO, ASSIGNOR TO THE DENVER ROCK DRILL MANUFACTURING COMPANY, OF DENVER, COLORADO, A CORPORATION OF DELAWARE.

FLUID-OPERATED MOTOR.

1,399,223.

Specification of Letters Patent.

Patented Dec. 6, 1921.

Application filed March 29, 1918. Serial No. 225,511.

To all whom it may concern:

Be it known that I, GUSTAVE M. NELL, a citizen of the United States, residing at Denver, in the county of Denver and State of Colorado, have invented certain new and useful Improvements in Fluid-Operated Motors, of which the following is a specification.

The present invention relates to so-called pneumatic hammers in which an expansive motive fluid is utilized for operating a piston.

The object is to provide a novel structure of a simple character that is highly effective for distributing motive fluid to the piston to actuate it, and permitting a free exhaust therefrom, at the same time obtaining a cushion to the piston at the limit of its stroke.

20 An embodiment that is at present considered preferable, is illustrated in the accompanying drawings, wherein:—

Figure 1 is a plan view of the tool,

Fig. 2 is a longitudinal sectional view therethrough,

Fig. 3 is a front elevation, and

Fig. 4 is a cross section on the line 4—4 of Fig. 2.

Similar reference numerals designate corresponding parts in all the figures of the drawings.

In the embodiment disclosed, a cylinder member is employed comprising a barrel 5 closed by a front head 6 and a rear head 7. 35 The head 6 is formed with a suitable chuck 8 to receive a tool, as a drill steel, a portion of which is shown at 9. The rear head 7 is provided with a suitable handle 10, and the cylinder member formed by the barrel and heads is maintained in assembled condition by side bolts 11 connecting the heads and clamping them firmly against the ends of the barrel 5, as will be evident. The cylinder member is formed with a piston chamber 12, 45 to the ends of which motive fluid is supplied through a channel 13 having ports 14 opening into the ends of said chamber, and preferably in communication with annular grooves 15 formed therein. Exhaust ports 50 16 open into the chamber at the ends thereof and just inside the groove 15, these ports also communicating with suitable grooves 17. A third exhaust port 18 opens into the piston chamber midway between the port 16, and is

also preferably in communication with an annular groove 19.

A reciprocatory sleeve valve 20 is located in the piston chamber and is provided with reduced ends 21 that form internal oppositely faced pressure shoulders 22. These reduced ends are received alternately by annular pockets 23 formed by reducing the heads 6 and 7 at their inner ends and where they enter the ends of the barrel. Ports 24 open from the supply ports 14 into said pockets. The sleeve valve is furthermore provided midway of its ends with an exhaust port 25 that is in constant communication with the exhaust port 18 of the barrel, and said sleeve valve has end exhaust ports 26 that are respectively movable into and out of communication with the exhaust ports 16, accordingly as the valve is shifted.

A reciprocatory piston is employed which includes a head 27 operating in the sleeve valve 20 with a forwardly extending hammer portion 28 adapted to strike against the rear end of the tool 9. This piston also has a rearwardly projecting boss 29 adapted to enter a corresponding recess 30 formed in the rear head 7.

Briefly described the operation is as follows: With the parts as shown in Fig. 2 the piston has completed its forward stroke, and the sleeve valve 20 has been moved rearwardly. In this position, the foremost supply port 14 is uncovered, while the rearmost supply port is covered by the rear end of the valve. Motive fluid therefore will enter the front end of the piston chamber and drive the piston rearwardly, the exhaust taking place through the ports 25—18 and 26—16. As soon as the piston head 27 covers the rear exhaust port 26, it will be evident that motive fluid will be trapped behind the piston and the pressure will rise. This not only constitutes a cushion, but also causes additional pressure against the rear internal shoulder 22 of the valve, overbalancing the pressure against the ends of the same and causing said valve to move forwardly. Upon the forward movement, it will be evident that the rear supply port 14 will be uncovered and the front supply port covered. At the same time, the rear exhaust port 26 will move out of communication with the port 16, while the front exhaust port 26 will be moved into communication with its coacting

exhaust port 16. The ports 25 and 18 remain in communication, and will now be in front of the piston head. A forward movement of the piston will thereupon take place 5 until the front limit of its stroke is reached, whereupon a rearward shifting of the valve will occur and the cycle of operations thus will be continued. The ports 24 are employed for balancing the pressure against the 10 reduced ends, insuring the proper action of the valve.

From the foregoing, it is thought that the construction, operation and many advantages of the herein described invention 15 will be apparent to those skilled in the art, without further description, and it will be understood that various changes in the size, shape, proportion and minor details of construction, may be resorted to without departing 20 from the spirit or sacrificing any of the advantages of the invention.

Having thus fully described my invention, what I claim as new, and desire to secure by Letters Patent, is:—

- 25 1. In apparatus of the character set forth, the combination with a cylinder member, of a continuous sleeve valve movably mounted within the cylinder member, a piston reciprocating in the cylinder member, means controlled by the sleeve valve for supplying motive fluid to the piston for actuating it, means for maintaining pressure in opposite directions against the valve, and means controlled by the piston on its movement for increasing the fluid pressure alternately in opposite directions against the valve to shift the same.
- 30 2. In apparatus of the character set forth, the combination with a cylinder member, of an open ended continuous sleeve valve movably mounted in the cylinder member, pockets in the cylinder member for alternately receiving the ends of the valve, a piston reciprocating in the cylinder member, 35 means controlled by the sleeve valve for supplying motive fluid to the piston for actuating it, and means controlled by the piston on its movement for increasing the fluid pressure alternately in opposite directions against portions of the valve outside the pockets to shift the same.

- 40 3. In apparatus of the character set forth, the combination with a cylinder member, of an open ended sleeve valve movably mounted in the cylinder member, pockets in the cylinder member for alternately receiving the ends of the valve, said valve having oppositely disposed internal pressure surfaces contiguous to said ends, a piston reciprocating in the cylinder member, means for supplying motive fluid to the pockets, means controlled by the sleeve valve for supplying motive fluid to the piston for actuating it, and means controlled by the piston on its 45 movement for increasing the fluid pressure

alternately against the surfaces when the adjacent ends are in the pockets.

4. In apparatus of the character set forth, the combination with a cylinder member, of a sleeve valve therein having a reduced end, 70 forming an internal shoulder, an annular pocket in the cylinder member to receive the reduced end, means for maintaining fluid under pressure in the pockets, a piston operating in the sleeve valve, means controlled 75 by the sleeve valve for supplying motive fluid to the piston to actuate the same, and means providing an exhaust through the sleeve valve behind the shoulder, whereby the piston traps motive fluid and produces 80 an increased pressure against said shoulder when the piston passes the exhaust permitting means to shift said valve.

5. In apparatus of the character set forth, the combination with a cylinder member 85 having a piston chamber, of means for supplying motive fluid to the ends of the piston chamber, a continuous reciprocatory sleeve valve operating in the piston chamber and movable across the supply means, said sleeve 90 valve having reduced ends forming oppositely disposed internal pressure shoulders, pockets in the ends of the cylinder member for receiving the reduced ends, said cylinder member having ports for maintaining pressure 95 against the ends of the sleeve valve when in the pockets, a reciprocatory piston operating in the sleeve valve, and means for permitting exhaust from opposite sides of the piston, including ports in the end portions of the sleeve valve, the piston passing said ports and building up pressure 100 against the internal shoulders for effecting the shifting of the valve.

6. In apparatus of the character set forth, 105 the combination with a cylinder member, of a sleeve valve therein having an intermediate exhaust port and exhaust ports near its ends, a piston operating in the sleeve valve and traversing the intermediate port to permit exhaust therethrough from opposite sides of said piston, exhaust permitting means with which the end ports alternately communicate upon the shifting of the valve, and means controlled by the operation of the 110 piston to shift the valve.

7. In apparatus of the character set forth, the combination with a cylinder member having a spaced terminal and an intermediate exhaust permitting means, of a sleeve 120 valve therein having an intermediate exhaust port in constant communication with the intermediate means of the cylinder member, and end exhaust ports respectively movable into and out of communication with the 125 end exhaust permitting means of the cylinder member, a piston operating in the sleeve valve and traversing the intermediate port thereof to permit exhaust through said port from opposite sides of said piston, means 130

controlled by the valve for supplying motive fluid to the piston to actuate it, and means controlled by the operation of the piston to shift the valve.

- 5 8. In apparatus of the character set forth, the combination with a cylinder member having a piston chamber and motive fluid supply ports opening into the ends of the same, said cylinder member furthermore 10 having an exhaust port opening into the ends of the piston chamber and a port between the end ports also opening into said piston chamber, a reciprocatory sleeve valve in the piston chamber having oppositely disposed pressure surfaces at its ends, said sleeve valve operating across the supply ports and having end exhaust ports movable into and out of communication with the exhaust ports of the cylinder member, the
- 15 sleeve valve furthermore having an intermediate exhaust port in constant communication with the intermediate port of the cylinder member, and a reciprocatory piston in the sleeve valve movable across the intermediate exhaust port thereof to permit the 20 exhaust therethrough from opposite sides of the piston, said piston also covering and uncovering the end exhaust ports and thereby building up pressure against the pressure surfaces of the sleeve valve to move the same 25 in opposite directions.
- In testimony whereof, I affix my signature in the presence of two witnesses.
